DESIGN FOR A HAIRDRESSING APPLIANCE

Raymond L. Barker, Chicago, Ill.

Application August 4, 1945, Serial No. 121,224

Term of patent 7 years

(Cl. D86—8)

To all whom it may concern:

Be it known that I, Raymond L. Barker, a citizen of the United States, residing at Chicago, in the county of Cook and State of Illinois, have invented a new, original, and ornamental Design for a Hairdressing Appliance, of which the following is a specification, reference being had to the accompanying drawing, forming part thereof.

Fig. 1 is a top plan view of a hairdressing appliance embodying my new design;

Fig. 2 is a side elevational view thereof;
Fig. 3 is an end elevational view thereof; and
Fig. 4 is a vertical sectional view taken in the plane of the line 4—4 of Fig. 1 looking in the direction indicated by the arrows.

I claim:

The ornamental design for a hairdressing appliance, as shown.

RAYMOND L. BARKER.
